WILLIAM P. FAULKNER, OF KANSAS CITY, MISSOURI.

RECORDED

MONEY-TRANSMITTING ENVELOP.

1,136,948.

Specification of Letters Patent. Patented Apr. 27, 1915.

Application filed July 10, 1914. Serial No. 850,162.

To all whom it may concern:

Be it known that I, WILLIAM P. FAULKNER, a citizen of the United States, and residing at Kansas City, in the county of Jackson and State of Missouri, have invented 5 a new and useful Money-Transmitting Envelop, of which the following is a complete specification.

My invention relates to money transmitting envelopes which are employed in transmitting money, checks and securities to and from banks and other depositories by mail, express, messenger or other transporting means, and the objects of my invention 10 are—First. To provide an inexpensive envelop for transmitting money and securities which will prevent removal of same until the remitter's seal is broken. Second. To provide a pocket for the envelop to hold 15 paper money and which may be folded to lie within the envelop and sealed simultaneously with the sealing of the envelop. Third. To provide a tearing cable within the envelop whereby the latter may be trans- 20 versely separated to expose the inclosure for verification and without breaking the remitter's seal. I accomplish these and other objects that will hereinafter appear by the means illustrated in the accompanying 25 drawings in which—

Figure 1. is a view of the envelop showing the same in normally unfolded condition and the transversely extending tearing cable attached thereto. Fig. 2. is a view of 30 the envelop showing the pocket formed and folded to lie within the envelop and showing the inclosures held in place by the pocket. Fig. 3 is a view of the envelop folded in operative form showing the method of 35 simultaneously sealing the envelop and pocket, and Fig. 4. is a view of the pocket portion of the envelop holding the inclosures after the envelop has been separated by the tearing cable.

Similar reference numerals refer to similar parts throughout the several views.

The numeral 1 indicates my money transmitting envelop in its normally unfolded condition, and which consists substantially 50 of an oblong sheet of suitable paper or fabric, preferably paper shaped to suitable form. The opposite ends of the sheet are cut slanting at the corners thereof to a point a little in excess of one fourth the 55 width of the sheet, and the intermediate portion of each end is rounded at the cor-

ners thereof to form end flaps 2 and 3. A V-shaped incision 4 is transversely made in the sheet at opposite sides thereof a distance inwardly from one end, and each incision is extended a little in excess of one fourth the width of the sheet. The V-shaped incisions 4 are designed and located for the specific purpose of thereby providing side flaps 5 and 6 which are adapted to 60 fold forwardly and overlap each other and be overlapped by the end flap 2, to form a pocket 7 to receive and hold the one end of a pile of currency, and also for the purpose of providing side flaps 8 and 9, which are 65 adapted to fold forwardly and overlap each other and be overlapped by the end flap 3, to form an envelop 10 to envelop the pocket 7 and the inclosures held thereby. The borders of the end flaps 2 and 3 and side 70 flaps 5 and 8 are each provided with an adhesive substance, preferably glue, for the purpose of attaching the flaps mentioned on the overlapped flaps.

A transversely extending line of perforations 11 is apertured in the sheet a little distance inwardly from the V-shaped incisions 4 and the same extends entirely across the sheet including the face and flaps of the envelop. A cable 12 of suitable material, preferably linen twine, is secured on the sheet inwardly adjacent the line of perforations 11, and parallel therewith, for the purpose of tearing and separating the envelop along the line of perforations whenever a pulling 80 pressure is exerted on the cable in reverse direction. The cable 12 is attached to the inner surface of the envelop by glue or other fastening device so that when the protruding end thereof, shown in Fig. 3, is 85 pulled in reverse direction the envelop will be torn and separated along the perforations, the latter operating to prevent the tearing process from damaging that portion of the envelop which envelops the pocket 90 100 105 110 115 120 125 Checks, drafts and other cash items are similarly placed one above the other on the statement, thus forming the pile 14 shown at 15. Bank notes are placed uppermost on the 5 pile and placed so that one end of the notes will extend to the folding line 16 of the end flap 2, the opposite end of the notes being located inwardly of the cable 12 a suitable distance to provide opportunity to examine 10 and count the notes without removing the same from the pocket 7. The side flap is then folded forwardly on the dotted line 17 over and upon the notes and the opposite side flap 5 is folded forwardly on the dotted line 18 so that the same will overlap the side flap 6, and is gummed thereto, when the end flap 2 is folded forwardly on the dotted line 16 over and upon the end portions of the side flaps 5 and 6, and is gummed thereto, 15 thereby pocketing the end of the pile of notes within the pocket 7. The pocket 7 is then folded forwardly on the dotted line 13 over and upon the bank notes and other inclosures so that the pocket 7 will lie within 20 the limits of the envelop proper, thereby folding the bank notes backwardly upon the inclosures. The side flap 9 is then folded forwardly on the dotted line 19 over and upon the inclosures and the pocket 7, and 25 the side flap 8 is folded forwardly on the dotted line 20 so as to overlap side flap 8, to which the former is gummed, the end flap 3 is then folded forwardly on the dotted line 21 so as to overlap the adjacent end 30 portions of the side flaps 8 and 9 and is gummed thereon, thereby completely enveloping the pocket 7 and the inclosures, as shown in Fig. 3. A cable 22 is successively passed through the overlapping side flap 8, 35 the overlapped side flap 9, the pocket 7 and the portion of the bank notes therein and the portion of the bank notes thereunder, and through and around one side of the envelop, where the ends of the cable are tied, 40 knotted and sealed, as shown at 23 in Fig. 3. The front portion of the envelop over the pocket 7 and outwardly of the line of perforations 11 is reserved for the remitter's address and other memoranda, as shown at 45 50 24 in Fig. 4.

When the envelop containing money and money items is received the end of the cable 12 is seized and pulled backward and thereby the envelop is torn and separated along 55 the line of perforations 11, and the inclosures thereby exposed. The money and money items are examined and counted and

compared with the remitter's statement. If the statement is verified the cable 22 is severed and the inclosures removed, the pocket 60 7 and the portion of the envelop thereon having the remitter's address and memoranda is filed for future reference, the separate portion of the envelop having the receiver's address thereon is discarded. This 65 arrangement is economical in time consumed and in space required for preserving the record of remittances. Moreover, the method described obviates the use of a knife or other sharp implement for opening the envelop thereby removing the danger of cutting and mutilating bank notes which have been indifferently and carelessly inclosed.

If an examination and count of the money and money items by the receiver discloses a 75 shortage in amount of items or money the pocket 7 in which the remittance is sealed is returned to the remitter for correction, thereby preventing confusion and correspondence and placing responsibility upon 80 the remitter, since the seal is unbroken and it being impossible to abstract any of the contents of the pocket without mutilating the same and leaving a fragment thereof with the sealed pocket.

Having described my invention, what I claim is:

A money transmitting envelop consisting of an oblong sheet of suitable fabric having a portion thereof separately provided with 90 oppositely disposed overlapping side flaps and with an end flap adapted to overlap the outer ends of said side flaps and thereby forming an envelop, the remaining portion of the sheet being separately provided with 95 oppositely disposed overlapping and united side flaps and with an end flap which overlaps the outer ends of said overlapping side flaps and is united therewith, said side flaps forming the side and said end flap the bottom of a pocket adapted to fold forwardly 100 at its open end and lie within said envelop portion, said envelop portion having a cross-wise extending line of perforations traversing the body and said side flaps, and a cable 105 secured on the inner sides of the envelop portion and extending along said perforations and adapted for totally separating the envelop at said perforations.

WILLIAM P. FAULKNER.
